UNITED STATES PATENT OFFICE.

CHARLES CHEERS WAKEFIELD, OF LONDON, ENGLAND.

CONDENSER-FEED LUBRICATOR.

986,330.

Specification of Letters Patent.

Patented Mar. 7, 1911.

Application filed January 24, 1910. Serial No. 539,788.

To all whom it may concern:

Be it known that I, CHARLES CHEERS WAKEFIELD, a subject of the King of England, residing at London, England, have invented certain new and useful Improvements in Condenser-Feed Lubricators, of which the following is a specification.

This invention is for improvements in or relating to condenser-feed lubricators.

10 It is well known that in lubricators of this class the oil chamber wherein the condensation and whence the feed takes place is liable to fracture owing to expansion of the oil in the chamber when the inlet and outlet are closed. It sometimes happens that the engineer having closed the inlet and outlet leaves some part of the apparatus open to the steam from the boiler so that the whole apparatus including the oil chamber becomes 15 heated and this heat is imparted to the imprisoned oil, which, seeking to expand fractures the chamber, as already stated. According to this invention this difficulty is overcome by providing the oil chamber with 20 a safety device. The safety device conveniently takes the form of a loaded valve that controls an outlet from the chamber.

In the accompanying drawing the condenser-feed lubricator is shown in elevation having fitted to it a safety device constructed according to this invention; the device and its immediately adjacent parts are shown in central vertical section.

The oil chamber A is provided with a 35 steam inlet B controlled by a cock B'. Within the chamber are two or more outlet tubes C C' that communicate with sight feed devices D D' respectively controlled by cocks D² D³. At the top of the chamber is a 40 filling orifice A' that is screw-threaded to receive a filling plug E. Surrounding the filling plug and formed on the top of the chamber is a circular flange or cup A². All these parts are well known.

45 Within the plug is a valve F that controls an outlet F' through the plug. This valve is loaded by a spring F² so that normally the outlet F' is closed. The valve F and its spring are mounted within a chamber E' in 50 the plug, which is closed by a screw cap F³ entered into the top of the plug. The cap provides a guide for the upper end of the valve F whose lower end is guided in a vertical portion of the outlet F'.

55 The operation of this device is as follows:—Steam is admitted into the chamber

A by the inlet B and cock B' which steam as it condenses displaces oil from the chamber. The oil thus displaced passes down one of the outlets C C', say the outlet C, whence it 60 passes through the sight feed device D which is controlled by the cock D². If lubrication is not required the cocks B' and D² as well as any other cocks, such for example as the cock D³, that control outlets from the 65 chamber are closed so that the chamber is closed on all sides. The steam jet commonly used for carrying the oil forward from the sight feed device is, however, sometimes left on by the engineer and it is in such cases 70 that the oil imprisoned in the chamber A gets considerably heated and bursts the chamber. With the apparatus constructed according to this invention, however, the oil as it expands forces the valve F back against 75 the load of its spring F² and escapes through the outlet F' so that no fracture occurs. The cup A² surrounding the valve receives the oil that is forced out and by unscrewing the plug E it can be again returned when the 80 chamber is cool.

The filling plug E and the cup A² have before been employed for the purpose of filling the chamber A with lubricant and these elements still serve the same purpose, 85 but in addition form part of the safety device that constitutes the present invention.

It will be seen that the safety device may take various forms without departing from the spirit of the invention and may be applied to construction of condenser-feed lubricators other than that shown by way of example in the drawing.

What I claim as my invention and desire to secure by Letters Patent is:—

1. In a condenser-feed lubricator the combination of, an oil chamber having working outlets, means for closing all the working outlets, a filling plug that closes the top of the chamber but has in it a safety outlet, a 95 valve in the filling plug for controlling the safety outlet, and a loading for the valve to normally close the same against pressures from within the chamber the loading being so adjusted that it will not yield to working 100 pressures but will yield to the expansion of liquid in the chamber when all other outlets are closed; substantially as described.

2. In a condenser-feed lubricator the combination of, an oil chamber having working 110 outlets, a cup or gallery at its top, means for closing all the working outlets, a filling plug

- for closing the top of the oil chamber and located within the cup or gallery, the plug having a chamber therein and a passage extending from the face of the plug within the oil chamber to the periphery of the plug above the cup or gallery, a valve mounted within the chamber in the plug, and a loading for the valve to normally close the same against pressures from within the chamber, the loading being so adjusted that it will not yield to working pressures but will yield to the expansion of liquid in the chamber when all other outlets are closed; substantially as described.
- 15 3. In a condenser-feed lubricator the combination of an oil chamber having working outlets and at its top a cup or gallery, means for closing all the working outlets, a filling plug for closing the top of the oil chamber situated within the cup or gallery, the plug having a chamber therein and a passage ex-

tending from the face of the plug within the oil chamber to the periphery of the plug above the cup or gallery, a valve mounted in the chamber in the plug, the valve having a 25 stem extending along the chamber, a spring mounted on the stem of the valve and arranged to keep the valve closed against all working pressures but will yield to the expansion of liquid in the chamber when all 30 other outlets are closed, and a screw-cap for closing the top of the chamber in the plug and arranged to form a guide for the stem of the valve and an abutment for the spring; substantially as described. 35

In testimony whereof I have signed my name to this specification in the presence of two subscribing witnesses.

CHARLES CHEERS WAKEFIELD.
